UNITED STATES PATENT OFFICE.

CHARLES L. SICARDI, OF NEW YORK, N. Y.

DESIGN FOR A SPRAYER-BODY.

SPECIFICATION forming part of Design No. 33,368, dated October 16, 1900.

Application filed September 4, 1900. Serial No. 29,011. Term of patent 3½ years.

To all whom it may concern:

Be it known that I, CHARLES L. SICARDI, a citizen of the United States, residing at Brooklyn borough, New York city, in the county of Kings and State of New York, have invented and produced a new and original Design for a Sprayer-Body, of which the following is a specification.

This design consists in a sprayer-body having a cylindrical body, a reversely-curved base, and a frustum-shaped foot part, said base having a nipple formed with two convex or ball-like parts connected by a portion of diminished diameter.

5 The design is illustrated in the annexed drawings, in which—

Figure 1 is a side elevation of the sprayer-body. Fig. 2 is a plan view of Fig. 1.

The cylindrical body is shown at 1 10 mounting a base 2, which, as seen, has the up-

per and lower parts reversely curved. The foot part 3 of the base is frustum-shaped. The base has a nipple or stem formed with two convex or approximately ball-like parts 4 and 5, connected by a portion or stem part 25 6 of diminished diameter as compared with the convex bodies 4 and 5.

The design gives a striking and characteristic appearance.

What I claim as new, and desire to secure 30 by Letters Patent, is—

The design for a sprayer-body as herein shown and described.

In testimony whereof I have hereunto set my hand in the presence of two subscribing 35 witnesses.

CHARLES L. SICARDI.
